United States Patent Office

Des. 207,866
Patented June 6, 1967

207,866

LIGHTING FIXTURE

Hendrik A. J. de Vos, Wenham, Mass., assignor to Sylvania Electric Products Inc., a corporation of Delaware

Filed June 30, 1966, Ser. No. 2,880

Term of patent 14 years

(Cl. D48—20)

FIG.1

I claim:

The ornamental design for a lighting fixture, as shown and described.
